UNITED STATES PATENT OFFICE

ROBERT SANFORD RILEY, OF WORCESTER, MASSACHUSETTS, ASSIGNOR TO RILEY STOKER CORPORATION, OF WORCESTER, MASSACHUSETTS, A CORPORATION OF MASSACHUSETTS

UNDERFEED STOKER

Application filed April 22, 1922. Serial No. 556,011.

This invention relates to a mechanical stoker of the underfeed type in which fuel is supplied through a plurality of retorts, each receiving fresh fuel at its upper or front end and discharging ash and refuse from the rear end thereof onto an overfeed grate extension and thence to the ash dump.

5 Adjacent retorts are separated by air-conducting side walls supporting the usual tuyère blocks and it is one of the objects of my invention to separately control the air supply for different parts or sections of these side walls and tuyère blocks and the overfeed grate section. This feature of my invention 10 is of particular importance in very large stokers in which the condition of the fuel bed may vary greatly in different parts of the furnace, rendering it very desirable to be able to independently increase or decrease the air 15 pressure at any desired point.

In one form of my invention, the sectional overfeed grate mounted at the rear of the retort has its middle portion fixed and the side portions mounted to move with the retort side 20 walls. It is a second object of my invention to provide a separate air supply for the fixed overfeed grate elements and particularly to combine this separate air supply for the fixed overfeed grate portion with the independent 25 air supply for different sections of the side walls.

Furthermore, my invention contemplates provision for suitable air supply for the rocking ash discharge or dumping plates at the 30 rear of the retorts and overfeed grates, and in the preferred form, I associate with the air supply for the dumping plates the air supply for the movable side elements of the overfeed grates.

40 An additional object of my invention is to provide means to prevent overheating of the clinker grinding and ash removing mechanism of my improved furnace.

45 My invention further relates to certain arrangements and combinations of parts which

will be hereinafter described and more particularly pointed out in the appended claims.

A preferred form of my invention is shown in the drawings in which

Fig. 1 is a partial plan view of my improved stoker;

Fig. 2 is a sectional elevation taken along the line 2—2 in Fig. 1;

Fig. 3 is a partial sectional elevation taken along the line 3—3 in Fig. 1.

Fig. 4 is a detail view of the driving mechanism of the clinker grinder; and

Fig. 5 is a sectional elevation of the clinker grinder, taken along the line 5—5 in Fig. 4.

Referring to the drawings, I have shown parts of a stoker which, in its general arrangement and construction, closely resembles a well known commercial type and includes a hopper 20 connected to a cylinder 21 from which coal or other fuel is forced by a ram 22 through a feed chute or casing 23 into the upper end of the associated retort. The casing 23 is mounted in the front wall 24 of the furnace and the ram 22 is regularly reciprocated by a connecting rod 25 actuated by a crank shaft 26. The shaft 26 is provided with a worm wheel 27 engaged and driven by a worm not shown, the mechanism thus far described being of the usual construction and forming no part of my present invention.

The retorts are inclined rearwardly and downwardly and are provided with side walls 28 preferably having lost motion connections 29 with the ram 22. The side walls 28 are thus reciprocated with the ram 22 during a portion only of each stroke of the ram. The extent of movement of the side walls may be increased as desired by placing U-shaped collars 30 on the lost motion connections 29, thereby reducing the lost motion between the parts. The side walls of adjacent retorts are spaced apart sufficiently to form air passages, the construction and function of which will be hereinafter described.

My improved stoker is provided with air

admitting ash discharge plates 60 pivotally mounted at the rear of the retorts and connected by an air conduit 61, to an air chamber 62 extending beneath the several retorts. A damper 63 may be provided to control the flow of air from the chamber 62 to the conduit 61.

5 A main wind trunk 64 is connected to the chamber 62 by a passage 65, controlled by a damper 66. The wind trunk 64 is also connected to a second air chamber 67 by a passage 68 controlled by a damper 69.

10 The separate side walls 28 of the retorts define air passages through which air is supplied to the tuyère blocks 71. Partitions 72 divide the side wall passages into upper and lower portions, the upper portion being in direct communication with the air chamber 67 and the lower portion being similarly connected with the air chamber 62. The tuyère blocks are thus disposed in two groups and the air pressure for each group may be separately controlled by means of the dampers 66 and 69.

15 A series of overfeed grates are provided between the rear ends of the retorts and the ash discharge plates 60 and these overfeed grates are shown as each comprising side portions 73 and 74, and an intermediate portion 75. The intermediate portion 75 is fixed in position and serves as a continuation of the stationary bottom of the retort, while the side portions 73 and 74 are movable with the retort side walls 28.

20 The middle portion 75 is separately connected by a passage 76 to the wind trunk 64, the flow of air to the grate portion 75 being controlled by a sliding damper 77. The air for the side overfeed grate elements 73 and 74 is preferably drawn from the air space 61 to which the ash discharge plates 60 are connected. Plates 78 (Fig. 3) separate the overfeed grate elements 73 and 74 from the lower air passage between the side walls 28.

25 Provision is thus made for supplying air at any desired pressure to the upper or lower sections of the tuyère blocks and to the middle section of the overfeed grate, and provision is also made for supplying air at the pressure of the air chamber 62 or less to the ash discharge plates 60 and to the overfeed grate elements 73 and 74.

30 The stoker shown in Figs. 1 and 2 also embodies a clinker grinder or roll 80 and a second series of ash discharge plates 81, mounted upon the rear or bridge wall 82, and receiving air from a passage 83. The discharge plates 81 are preferably arranged in sections which may be moved separately or in small groups by the actuating mechanism shown, 35 which comprises a shaft 85 having arms 86 connected by links 87 to the plates 81 and having additional arms 88 connected by links 89 to lifter rods 90.

35 A hand wheel 91 is threaded on each rod 90 and a spring 92 is interposed between the

hand wheel and the upper face of a fixed bearing block 93. When the hand wheel 91 is turned to draw the rod 90 upward, the plates 81 are advanced toward the clinker grinder 80. The springs 92 permit the plates 81 to yield when necessary to avoid breakage.

40 The preferred form of the clinker grinding mechanism is shown in Figs. 4 and 5, the roll 80 preferably comprising a pipe or tube 95 rotatable in bearings 96 and enclosed by 45 sectional plates 97 in which grinding teeth 98 (Fig. 2) are secured. The details of construction of these parts of the grinding mechanism form no part of my present invention, and a complete description thereof will be found in my prior application Serial No. 386,848, filed June 5, 1920. The roll may be intermittently actuated by a pawl 98 (Fig. 4) and ratchet wheel 99, the pawl being connected by a link 100 to actuating means not shown.

45 It is found that the clinker grinding rolls are often seriously distorted by the extreme heat to which they are occasionally subjected, and, as stated, it is an object of my invention to provide means to prevent such overheating of the rolls. For this purpose the ends of the tube or pipe 95 are left open or are only partially closed by rings or flanges 101 and a water pipe 102 is introduced into one end of 50 the pipe 95. The pipe 102 is provided with a nozzle 103, controlled by a valve 104, suitably connected by an arm 105 and link 106 to a sleeve 107. This sleeve is slidable on the pipe 102 and is controlled in position by any 55 suitable thermostat such as a bellows thermostat 108 of well known construction, one end of which is secured to a collar 109 fixed on the pipe 102.

60 The parts are so arranged that expansion and contraction of the thermostat, due to increase and decrease of temperature respectively, will move the sleeve 107 and turn the valve 104 and control the escape of water through the nozzle 103. This water will prevent such undue rise of temperature in the roll as would cause distortion thereof.

65 The advantages of my invention will be readily apparent. By the construction shown, I am able to distribute and control the air supply so that the air pressure on either the upper or lower portions of the side walls and tuyère blocks and also on the fixed portion of the overfeed grate may be raised or lowered as desired and without reference to the pressure in the other portions of the stoker.

70 I have also provided for a suitable supply of air, at any pressure not greater than that on the lower set of tuyère blocks, for the air-admitting ash discharge plates and for the movable portions of the overfeed grate. In addition to this, I have provided novel means for preventing distortion and injury to the grinder rolls.

It will be evident that changes and modifications can be made in my invention without departing from the spirit and scope thereof as set forth in the claims, and I do not wish to be otherwise limited to the details herein disclosed, but what I claim is:—

1. An underfeed stoker comprising walls defining a retort having a stationary bottom, an overfeed grate section having a stationary middle portion, serving as an extension of the retort bottom, side portions which are movable lengthwise of the stoker relative to the stationary middle portion and means for actuating the movable portions of the grate.
2. An underfeed stoker comprising walls defining an underfeed retort having a stationary bottom, an overfeed grate section having tuyère openings therein, said section having a stationary middle portion which serves as an extension of the retort bottom and side portions which are movable lengthwise of the stoker, means for supplying air under pressure to said overfeed grate section and means for actuating the movable portions of the grate.
3. An underfeed stoker comprising a stationary bottom and movable side walls forming a retort therebetween, tuyère blocks on the side walls, a stationary overfeed grate section having tuyère openings therethrough which serves as an extension of the retort bottom and overfeed grate sections on each side of said stationary section which are movable lengthwise of the stoker with said retort side walls.
4. An underfeed stoker comprising retorts having stationary bottoms and longitudinally reciprocable side walls arranged to provide an air space beneath the stoker, tuyère structures surmounting said side walls and adapted to receive air from said space and deliver it to the retorts, a transverse partition extending between the reciprocable side walls which divides said space into forward and rear compartments, both of which deliver air to the retort tuyères, an air duct, means forming separate passages directly connecting said duct with each of said compartments, and separately adjustable damper means controlling the air flow through each passage, whereby the pressure in either compartment may be regulated independently of the pressure in the other.
5. An underfeed stoker comprising walls defining retorts having tuyères therebetween, an overfeed grate extension at the rear end of said retorts having tuyère openings therethrough, means including a transverse partition extending beneath the retorts and forming forward and rear compartments, each adapted to supply air to part of the tuyères between the retorts, partitioning means forming an air compartment beneath the overfeed grate extension for supplying air thereto, an air duct, means forming sep-

arate passages directly connecting said duct with each of said compartments, and separately adjustable damper means controlling the air flow through each passage, whereby the pressure in any compartment may be higher or lower than the pressure in any other compartment.

In testimony whereof I have hereunto affixed my signature.

ROBERT SANFORD RILEY.
